[57] **CLAIM**

The ornamental design for a display station for a data processing system, as shown.

DESCRIPTION

FIG. 1 is a front three-quarter perspective view of a display station for a data processing system incorporating our new design;

FIG. 2 is a rear three-quarter perspective view thereof; FIG. 3 is a bottom plan view thereof;

FIG. 4 is a front elevational view thereof;

FIG. 5 is a top plan view thereof;

FIG. 6 is a left side elevational view thereof.

FIGS. 1 and 2 show the operator-adjustable display head tilted slightly upward on the base unit. FIGS. 3-6 show the display head in its horizontal, zero-tilt position.

FIG. 1

FIG. 2

FIG. 3

FIG. 4

FIG. 5

FIG. 6
